UNITED STATES PATENT OFFICE.

HAL P. GALBREATH, OF POPLAR BLUFF, MISSOURI.

COLLAPSIBLE COOP.

1,344,877.

Specification of Letters Patent. Patented June 29, 1920.

Application filed November 30, 1918. Serial No. 264,866.

To all whom it may concern:

Be it known that I, HAL P. GALBREATH, a citizen of the United States, residing at Poplar Bluff, in the county of Butler and 5 State of Missouri, have invented certain new and useful Improvements in Collapsible Coops, of which the following is a specification.

This invention comprehends generally 10 improvements in that class of inventions known as metallic shipping and storing vessels and more particularly relates to a collapsible coop.

It is the principal aim and object of this 15 invention to provide a device of the above mentioned character designed with sides and ends swingably connected to the base and detachably engageable with each other and provided with a top carried by the ends 20 and detachably engageable with the sides whereby the coop may be placed in an extended and locked position or else collapsed to a small compact form when not in use so as to occupy only a minimum amount of 25 space when being shipped.

It is an equally important object of this invention to provide a device of the above mentioned character wherein the ends of the coop are constructed in relatively movable sections one of which is formed with 30 means for detachably engaging the end portions of the sides of the coop for insuring of the maintenance of the coop in an extended position while coacting therewith, 35 to further increase the rigidity of the device when extended are catch means, carried by the top and detachably engageable with the upper portions of the sides of the coop.

It is a more specific object of this invention 40 to provide a device of the above mentioned character wherein a closure of improved construction is slidably mounted on the top of the coop for closing the opening in the top while acting in conjunction with 45 the closure is retaining means therefor.

Among the other aims and objects of this invention may be recited the provision of a device of the above mentioned character wherein the number of parts are comparatively few, the construction simple, the cost of production low and the efficiency high.

Other objects, as well as the nature, characteristic features and scope of this invention will be more readily apparent from 50 the following description taken in connection with the accompanying drawings and

pointed out in the claims, forming a part of this specification.

The invention is clearly illustrated in the accompanying drawings, in which:

Figure 1 is a side elevation of the improved crate,

Fig. 2 is a top plan view thereof,

Fig. 3 is an end elevational view of the crate,

Fig. 4 is an enlarged fragmentary elevational detail of the clutch means on the top,

Fig. 5 is an enlarged fragmentary horizontal sectional detail showing the retaining hooks at the ends of one of the end sections,

Fig. 6 is a longitudinal central section through the top and taken on line 6—6 of Fig. 2,

Fig. 7 is a transverse sectional detail taken on line 7—7 of Fig. 2, and

Fig. 8 is a longitudinal central sectional view through the coop showing the same in a folded compact form.

Similar characters of reference are employed in all of the above described views, to indicate corresponding parts.

Referring now, more particularly to the accompanying drawings there is provided 85 a base 1 desirably composed of a plurality of boards 2 having tongue-and-groove edges 3 and the under surface of this base is provided with a plurality of transversely and longitudinally extending spaced and intersecting grooves in which are respectively arranged bracing wires or rods 4, the end portions of which are bent upwardly and engaged in the end and side edges as shown at 5 terminating in eyes 6, disposed slightly 90 above the upper surface of the base while mounted in the eyes is a rectangular frame 7.

Swingably connected to the opposite side portions of the frame 7 are the sides generally designated by the numeral 8. These sides in the present instance are of an open work nature being composed of an inverted substantially U-shaped support 9 formed of relatively stiff wire and longitudinally 105 and transversely extending and intersecting bars 10, also formed of wire. The inner terminals of the sides of the support 9 and the transversely or vertically disposed bars 10 terminate in eyes 11. By this construction, it is apparent that the sides may be 110 arranged perpendicularly of the base or

swung inwardly toward each other to lie on the base when it is desired to collapse the coop.

As intimated, sectional ends have been 5 provided and in the present instance consist of inner sections generally designated 12 and relatively swingable outer or upper sections 13. Each inner section 12 is composed of a plurality of vertically disposed 10 bars 14 of wire the respective ends of which terminate in loops 15 while all of these vertical bars are joined by a transverse bar 16, also of wire. The innermost 15 eyes 15 are swingably engaged about the end portions of the frame 7 as indicated in the Fig. 3 so that the sections may be arranged vertically or swung inwardly toward each other to lie over the sides 8, when the latter are folded, as is apparent. Each 20 outer section 13 is composed of substantially U-shaped supports 17 of relatively heavy or thick wire and like the section 12 is of an open work nature being composed of vertically and transversely disposed 25 and intersecting bars 18 and 19 respectively the ends of which are formed with eyes 20 and 21 respectively. The inner eyes 20 are swingably engaged about the medial portion of the support 18 while 30 the eyes 21 are rigidly engaged with the side portions of the said support. In connection with the support 17 it is to be noted that at the points of distortion between the intermediate and side portions the wire 35 forming the said support is folded upon itself and bent to provide opposed inturned hooks 22 designed to be engaged at times when the device is extended with the side portions of the support of the side 8 as 40 indicated to facilitate the maintenance of the coop in a set-up position.

A toy generally designated by the numeral 23 is now employed and consists of a rectangular and relatively heavy frame 24 between the sides and end portions of which are arranged and connected the eye terminals of the transversely and longitudinally extending and intersecting bars 25 and 26 respectively, the terminal eye portions of 50 which are engaged with the adjacent portions of the frame 24. The upper eyes on the vertical bars 18 are swingably engaged with the end portions of the frame 24 so that the frame will move toward the base upon 55 the folding of the sections 12 and 13 in the manner indicated in Fig. 8 so that the device will occupy a compact form and a minimum amount of space when not in use.

As intimated, the open top has been 60 provided with an opening 27 so that access may be had within the interior of the coop when it is in an extended position. This opening is preferably provided by cutting away the medial longitudinal and adjacent bars 26 65 joining the adjacent terminals with the ad-

jacent transverse bars 25 as indicated at 28. A closure generally designated by the numeral 29 is now provided for the opening 27 in the cover and is composed of spaced transverse bars 30 formed of suitable wire 70 and joined by spaced longitudinally extending bars 31. Eyes are formed at the terminals of the transverse bars as shown at 32, the forward eyes being slidably arranged on the adjacent longitudinal bars 26 of the 75 cover while the other eyes are slidably engaged on longitudinally extending guide rods 33 suspended beneath the bars 26 on which the forward eyes 32 are engaged, the arrangement being clearly indicated in the 80 drawings. A spring retaining catch 34 is mounted on the top and is designed to releasably hold the closure in a closed position.

Coöperating with the hooks 22 for retaining the coop in extended position, are snap hooks 35, the shanks of which are connected to certain of the transverse bars 25 so that the curved bills are disposed in a position 85 so as to engage the medial portion of the support 9 of the sides 8 being prevented from displacement by the leaf retaining springs 36 forming part of the snap hooks 35, as is apparent.

In use in placing the coop into an extended form it is only necessary to raise the top away from the base, this action straightening sectional sides whereupon the sides 8 are swung upwardly and engaged with the hooks 22 and the snap hooks 35. In collapsing the crate, the sides 8 are disengaged and swung inwardly toward each other to lie on the base 1 whereupon the innermost sections 12 of the ends are swung inwardly to lie over the sides 8 and during this action 105 the outermost sections 13 are swung outwardly so as to overlie the sections 12, this action drawing the cover or top toward the base so that the parts will assume the position as indicated in Fig. 8.

It is believed in view of the foregoing description that a further detailed description of the operation of the invention is entirely unnecessary. Likewise, it is believed that the advantages of the invention will be 115 readily apparent.

Still further embodiments of the invention than those herein especially defined may be resorted to as conditions or preference may dictate, as may be in keeping with the hereto 120 appended claims.

Having thus fully described the invention, what is claimed as new and desired to be secured by Letters Patent, is:

1. A folding coop comprising a base, rods 125 positioned beneath the base and having their end portions carried uprightly and terminating in eyes above the base, a frame extending above and about the base, the frame being formed from a strip of rod material 130

bent to conform to the contour of the base and passing through the eyes, side and end walls having their lower edge portion loosely connected with the frame to pivotally mount 5 the walls, a top having loose connection with one set of walls, and means for releasably connecting the walls when the coop is in a setup position.

2. A folding coop comprising a base, 10 transverse and longitudinal rods positioned beneath the base and having their end portions carried upwardly and terminating in eyes, a frame formed of a strip of rod material bent to pass through the eyes, side 15 and end walls having their lower edge por-

tion loosely connected with the frame to pivotally mount the walls, said walls being formed of rod material, the ends of the rod material of one set of walls bent to form hooks for engaging adjacent portions of the 20 rod material of the other sections of wall to provide a releasable connection between the walls, permitting one set of walls to be moved to a set up position and retained in the set up position through the medium of 25 the second set of walls, and a top having loose connection with one set of walls.

In testimony whereof I affix my signature hereto.

HAL P. GALBREATH.
